UNITED STATES PATENT OFFICE

145,801

DESIGN FOR A BUILDING

Harold Paul Hummel, Mount Carmel, Pa.

Application November 27, 1945, Serial No. 124,095

Term of patent 14 years

(Cl. D13—1)

To all whom it may concern:

Be it known that I, Harold Paul Hummel, a citizen of the United States of America, residing at Mount Carmel, in the county of Northumberland and State of Pennsylvania, have invented a new, original, and ornamental Design for a Building, of which the following is a specification, reference being had to the accompanying drawings, forming a part thereof.

In the drawings:

Figure 1 is a top plan view of a building showing my new design.

Figure 2 is a front elevational view of the same.

The door and window arrangement shown in Figure 2 of the drawings is repeated throughout the periphery of the building.

I claim:

The ornamental design for a building, as shown and described.

HAROLD PAUL HUMMEL.
